ELEVATOR CONTROL SYSTEM

Application filed December 1, 1926. Serial No. 151,872.

My invention relates to elevators and more particularly to an intercepting push-button control system for a bank of elevators.

One of the objects of the invention is to provide an intercepting control system in which the start of the car is effected manually by momentary actuation of a car switch combined with selectively operable hall and car push-buttons which effect only automatic car stops, which function differentiates it from other well known systems wherein such buttons control both starts and stops.

Another object of the invention is to provide an intercepting control for a bank of elevators, comprising only a single set of hall buttons, i. e., one "up" and one "down" button per landing to dominate all the cars forming the bank, whereby momentary operation of said buttons renders operable certain elements so that any car of the bank first to reach said landings and whose direction of movement corresponds to the buttons pressed, will be automatically intercepted at such landings.

Another object of the invention is to provide an intercepting control system comprising selectively operable car buttons and a system of circuits to effect automatic car stops successively at landings toward which the car is moving. These buttons may be set by the car operator as the passengers in the car call their floors, and for any one direction of car travel, all set buttons remain operative during travel of the car toward landings corresponding thereto, and each is re-set automatically when the car stop is effected at floors corresponding thereto.

A still further object of the invention is to provide means whereby each car operator may at will, when certain contingencies arise as for example when a car becomes fully loaded and no other stops are desired until the limit of travel or other predetermined point is reached, render ineffective with respect to his particular car only the stopping function of the intercepting control as rendered operable by actuation of the hall-buttons and in this manner transfer the stopping effect of the intercepting control so that the second car to come along in the same direc-

tion as the first and provided its transfer means are not actuated, will be subjected to said stopping effect. Hence with the use of such transfer means, any car operator may at his election render the hall-button system ineffective to stop his car and the latter will then continue as express to any desired landing beyond as determined by him. However, operation of these transfer means does not interfere with the automatic stopping operation controlled by the car buttons to let passengers off at desired landings.

A still further object of the invention is to provide in an intercepting system of control, hall-buttons of the momentarily actuated type which upon completing their function to effect automatic car stops, are automatically re-set individually in accordance with the direction of car travel.

Other objects of the invention will be pointed out more fully hereinafter, the novel combinations of elements and arrangement of parts being pointed out in the appended claims.

Referring now to the accompanying drawings, Fig. 1 illustrates in a diagrammatic manner, an intercepting automatic push-button control system for a bank of single speed elevators, with apparatus and a system of circuits arranged in accordance with the present invention;

Fig. 2 illustrates in a diagrammatic manner, an intercepting automatic push-button control system for a bank of elevators more particularly of the two speed type; and

Figs. 3, 4 and 5 illustrate modified forms of controlling apparatus to be used in conjunction with the present intercepting control for a bank of elevators of the multiple speed type.

Referring now to Fig. 1, three cars form the bank and are designated A, B and C, each of which is operated by its hoisting motor M of any suitable type through the intermediary of any well known system of driving sheaves, roping or gearing (not shown). The controlling elements for one of the cars will now be designated and since they are the same for each car system, the designation for one system will suffice for all.

In the system illustrated herein the cars are shown as serving three floors designated 1, 2 and 3, and it will be understood that the system may serve as many other floors as may be desired and for the purpose of this description it will be assumed that floor 3 is an intermediate floor. Floor-stopping switches designated D may be of the type positioned in the elevator hatchway to be actuated automatically by movement of the car through the intermediary of a cam E fixed on the elevator car. Each stopping switch for intermediate landings comprises a pivotally supported switch arm 4 carrying contactors 5 and 6 co-acting with fixed contactors 7 and 8. The contactors of the three sets of floor stopping switches of the combined bank of cars, control circuits which are dominated and rendered operable by a single set of hall-buttons comprising only two buttons per floor, designated 9 and 10 to effect "up" and "down" car stops for all three cars forming the bank, and in effect it may be said, therefore, that the hall-buttons function to intercept the cars at landings toward which they are moving, because otherwise the cars will pass by any landings whose corresponding car buttons are not set for stop by the car operator. Such intercepting function eliminates necessity for exercise of attentiveness on the part of the car operator and is rendered effective without his knowledge and so eliminates the necessity for car signals whereby passengers designate their presence at landings.

The stopping switch arm carries an additional contactor 11 to coact with fixed contactors 12, the contactors of the stopping switches which form a set for each particular car system, controlling circuits which are individual to their own particular car system solely. The circuits for each system are controlled by one set of selectively operable car buttons 13, 14 and 15 by means of which the car for either direction of travel is controlled automatically to stop successively at landings toward which it is moving and whose corresponding buttons are pressed.

According to the present invention as illustrated in Fig. 1, the floor stopping switches are actuated by a fixed cam E on the car in a well known manner according to standard practice. However, the manner in which they function in order to effect automatic stops is materially different in that their contactors are normally open-circuited and when a switch arm is actuated by the car cam, these contactors are engaged only momentarily to close certain circuits which momentarily energize certain elements. When the car reaches a landing, the cam actuates the switch arm so that its contactors assume a neutral position with respect to the "up" and "down" fixed contactors. Upon movement of the car to continue its travel, the cam will

move the switch arm contactors to a point beyond the opposite set of fixed contactors to an open-circuited position.

There is one hall-button at the lower floor, one at the upper floor (not shown), and two at each of the intermediate floors. In each car there are as many car buttons as there are floors served. All of these buttons are of the automatic re-set type in which their contactors 16 are closed by pressing a button and remain closed to maintain the circuit. Each has a winding 17 which is energized at the time its particular button completes its function of effecting a car stop, and thereby re-sets the button or, in other words, opens its contactors 16.

A manually operable car switch 18 is adapted for actuation in a one-way direction from a neutral position as shown to effect start of the car for either direction of travel as predetermined by "up" and "down" direction relays 19 and 20 respectively which are controlled and properly set by switches 21 and 22 actuated automatically by a cam 23 on the car when it reaches its limits of travel. By movement of the car switch from its neutral position as shown, in a reverse direction to said one-way movement, operation of auxiliary direction relays 24 and 25 is effected in a manner properly to set the direction relays 19 and 20 independently of the car operated hatchway switches 21 and 22, to establish direction for car travel in a reverse direction. When direction for reverse car travel is thus established, the car can then be started in said reverse direction by returning the car switch to neutral position and continuing its movement in the heretofore mentioned one-way direction. In this manner provision is made whereby the car operator may effect reverse operation of the car at will at any intermediate point of car travel, thereby eliminating necessity of running the car to the limits to effect such result.

Electro-magnetically operable reversing switches R and R' control the hoisting motor M for "up" and "down" directions of car travel respectively and are provided with windings 26, 27 respectively, adapted by one-way movement of the car switch to be energized selectively as determined by whichever direction relay 19 or 20 is in closed position. A relay 28 having a winding 29 dominated by the car switch is provided with contactors 30 to control a self-holding circuit for the reversing switch windings which in effect means that the car "starts" are effected by momentary actuation of the car switch and thereafter the hoisting operation is continued automatically as effected by said relay 28.

An electro-magnetically operable stopping switch S is operable by momentary energization of its winding 31 to effect automatic stops by opening normally closed contactors 32 included in the common feed wire or said self-

holding circuit for said reversing switch windings, the energization of said winding 31 to control the car stops being subject to the control of the selectively operable hall-buttons and car buttons together with the floor stopping switches. A transfer switch 33 is provided whereby a car operator may at will render ineffective the stopping action of the intercepting control elements in so far as his particular car is concerned, the effect being to transfer the stopping effect to the next car to come along in the same direction.

Operation of the elements through a complete cycle together with a detailed description of the electrical circuits will now be described.

In the class of elevator service for which the present intercepting control system is intended, each car ordinarily serves all landings from one end to the other end of travel before reversing. For such service each car has an operator to control the car "starts" by actuation of the car switch 18 and the car will stop automatically and successively at all landings toward which it is moving whose corresponding car buttons are pressed, the car buttons being set by the car operator when the car passengers call their floors. Passengers at the landings can by pressing the "up" or "down" hall buttons, intercept the first car of the bank to reach such landings, whose direction of travel corresponds to the hall-buttons pressed.

To effect start of a car the operator moves the car switch momentarily so that segment 34 engages contacts 35 thus momentarily closing an energizing circuit for the winding of one of the reversing switches, depending on which direction relay is closed. For the purpose of this description I will assume that car B is at the landing 1 for which position thereof the cam 23 opens switch 22 to reset or open the "down" direction relay 20 and close the "up" relay 19, (as fully described herein-after), which thereby closes at the contactors 40 a circuit for the "up" reversing switch winding 26 so that now the car switch circuit energizes the "up" reversing switch winding 26, and the "up" reversing switch will now close and initiate the hoisting operation by the motor M in a well known manner. The circuit for the "up" reversing switch winding 26 may be traced as follows:—from plus wire 42, contactor 43, segment 34 to contactor 35, wire 44, relay winding 29, wire 45, contactors 32 of switch S, wire 46, contactors 40 of the "up" direction switch 19, wire 47, through "up" reversing switch winding 26 and thence by wire 48 to the minus main designated 49.

The circuit just traced includes the relay winding 29 and reversing switch winding 26 in series, and the former now being energized will close the relay contacts 30 thereof closing a self-holding circuit including said windings 29 and 26 and in this manner the

reversing switch will be held closed independently of the car switch which can now be centered without stopping the hoisting operation.

The self-holding circuit may be traced as follows:—branching from the plus wire 42, wire 51, contactors 30, thence through relay winding 29 and so on through the "up" reversing switch winding 26 and to the minus main as traced above.

It will at this point be observed that the normally closed contactors 32 of the stopping switch S are included in the self-holding circuit just traced for the "up" reversing switch winding and by rendering the energization of the winding 31 of the stop switch S subject to the control of the car buttons and hall push-buttons and associated floor stop switches through a system of electrical circuits hereinafter to be traced, said stop switch will, by momentary energization of its winding 31 separate its contactors 32 to open said self-holding circuit and effect stops of the car successively at all landings toward which it is moving whose car or hall push-buttons such as are set, correspond to movement of the car.

Now at this point reference will be made to the systems for the other two cars A and C which form the bank, because they each comprise one of these stopping switches S, and the system of circuits for all three switches are coordinated and interrelated in a manner subject to the control of the single set of hall push-buttons which comprises only one "up" and one "down" button for each floor served. However, the system of circuits for the stop switch S of any one car system as controlled by the car buttons is individual to that car system only and, therefore, will not interfere with, or be subjected to interference from the hall-button control circuits.

The circuit for the winding 31 of any one of the switches S,—take that of the system for car B for example,—may be traced from the plus wire 41, through winding 31, wire 55 to the "up" and "down" relay contactors 56, 57 respectively, whereat the circuit is divided to form two feed wires 58 and 59, controlled by the "up" and "down" contactors 56 and 57. The wire 58 connects in parallel all the "up" contactors of the floor stopping switches for any one car system and likewise the wire 59 connects in parallel all the "down" contactors of the floor stopping switches for any one system, and the "up" and "down" contactors of all three floor stopping switches at any one floor, are connected in parallel by wires 60 and 61 respectively controlled at each floor landing by the "up" and "down" hall push-buttons 9 and 10 respectively.

In order now to illustrate the manner in which a car is intercepted by actuation of the hall push-buttons let it be assumed that car B is now ascending from the first floor landing, car C descending from a landing above the

third floor, and car A at rest at the first floor landing. Assume further that for car B none of the car buttons is set or pressed in which case the car B will ordinarily pass by the landings. By pressing the third floor "up" hall-button 9, all the floor stopping switches for the third floor of any car of the bank traveling in an ascending direction toward said landing are thereby rendered effective to effect a car stop at such landing, and hence any ascending car of the bank first to actuate its third floor stopping switch will be the car which is intercepted.

Car B being the first will in its approach to the third floor landing bring the cam E into engagement with the stopping switch roller 63 to rock the floor stopping arm to close-circuit the "up" contactors 5 and 7 momentarily, the continued movement of the car causing the cam to disengage or open-circuit said contactors, so that the switch arm now assumes a neutral position with respect to the "up" and "down" contactors. The "up" contactors coacting in this manner, complete a momentary energizing circuit for the stop switch winding 31 and the stop switch S will now open its contactors 32 to open the self-holding circuit for the reversing switch winding and in this manner effect a car stop. The circuit for the winding 31 as completed may be traced as follows: from the plus main 41, wire 62, winding 31, wire 55, contactors 56, wire 58, up contactors 5 and 7 of the third floor stopping switch for car B, wire 64 to a junction 66 with the common "up" wire 60, through "up" push-button contactors 16, thence through winding 17 to the minus line. Since the circuit just traced includes the "up" push-button winding 17, the latter will operate to open its contactors 16 and in this manner it may be said the push-button is reset. Car B in its ascent, will when moving away from each floor actuate each floor stopping switch to momentarily close and again open-circuit the "down" contactors 6 and 8, but such closing thereof is ineffective to complete a circuit to effect a car stop if a "down" hall push-button is pressed because of the fact that for the B car system, the circuit for the stopping switch winding 31 as controlled by the down wire 59 etc., is now open at the "down" direction switch 20, which is not actuated to closed position until the car reaches the top floor landing. This ineffective circuit may be traced as follows: from wire 62 of the car B system, through winding 31, wires 55 and 59 now open-circuited at the contacts 57 of the "down" direction switch 20, the wire 59 including the lower contacts of the transfer switch 33 and connecting all down stop contacts 6 in parallel. The contacts 6 coact with their respective fixed contacts 8, each of which connects with the minus main 49 by way of its associated wire 61

"down" hall push-button contacts 16, and re-set winding 17.

It will here be pointed out that since the "up" contactors of all three stopping switches at any one floor are connected by normally open circuits in parallel, and likewise with the "down" contactors, and the "up" and "down" feed wires 58 and 59 are rendered effective by the direction relays, the present intercepting system as a whole, and through the agency of only one "up" and one "down" hall-button per landing, is operable to intercept at any landings the first car to reach it, and only such car will be intercepted whose direction of travel corresponds to the "up" or "down" button pressed, or in other words any car ascending is responsive only to "up" buttons at landings toward which the car is moving, and any car descending is responsive only to "down" buttons at landings toward which the car is moving.

Wires 60 and 61 are common to the up and down contactors respectively of all three stopping switches at any one floor, and include in circuit therewith the "up" and "down" push-button windings respectively, any such button will, therefore, be re-set whose direction corresponds to the direction of the car stopped, or in other words, an ascending car automatically re-sets any "up" hall-buttons, and a descending car automatically re-sets only "down" hall-buttons, such re-setting for the buttons of any one floor being effective simultaneously with the stopping or intercepting operation of the said first car.

The system of electrical circuits and apparatus as rendered effective by the car buttons to control car stops will now be described and for this purpose consider car B started from the first landing in the manner heretofore described. These car buttons may be set by the car operator in response to call for stop desired of the car passengers, and we will assume that car buttons 14 and 15 are set, they remaining in such set position after being momentarily pressed. Car B will now stop successively at the second and third floor landings as effected when the car cam E actuates the stopping switches at said floors to momentarily close the contactors 11 and 12. Such momentary closure of these contactors closes an energizing circuit for the winding 31 of the stopping switch S which circuit after passing through said winding includes the car buttons in parallel and is independent of the circuits controlled by the hall push-buttons and may be traced as follows:—from the plus main 41, wire 62, through the winding 31, thence by wire 69, and to car button re-set magnet windings 17 in parallel, through the second floor car button contacts 16, wire 72, floor stopping switch contactors 11 and 12, and thence by way of wire 73 to the minus main. The energizing circuit for the winding 31 now being com-

pleted, effects operation of the stopping switch S to open its contactors 32 to effect a car stop in a manner as heretofore pointed out. In like manner, the actuated car button 5 15 renders the third floor stopping switch contactors 11 and 12 operable to control the energizing circuit for the winding 31 to effect a car stop at the third floor landing. It will be remembered that the circuit for the stopping switch winding 31 includes the car push-button winding, in this instance the winding 10 for the car button corresponding to the second floor landing, which winding now being energized will operate to re-set or open-circuit 15 the second floor car push-button contactors 16. In like manner, all car push-buttons which are set, will be automatically re-set individually, and simultaneously with the stopping operation at landings corresponding thereto. Thus, a single set of car buttons 20 can be used for both directions of car travel and the fixed contactors 12 of the floor stopping switches can be connected by a common wire. Even though the contactors 11 of the 25 floor stopping switch arms are actuated for any one direction of car travel to engage both contactors 12 at any one floor, in the first instance as the car moves toward the landing in stopping, and in the second instance as the 30 car after starting continues its movement away from the landing, such second engagement will not have any effect because at such time, the corresponding car button is in re-set position as effected at the time the car stop 35 is made.

At this point it will be noted that the controlling circuit just traced for the stop winding 31 as controlled by the car buttons is individual to the car B system only. Likewise 40 the car button controlled circuits for the other two car systems are individual to those particular systems only. Hence, by such independence of the car button controlled circuits with respect to the parallel system of circuits 45 for the bank of elevators as controlled by the hall push-buttons, the car buttons and associated circuits of any one system will function to control the stops for the car of that one system only, excepting under one certain circumstance remote as to occurrence, 50 as when two cars traveling in the same direction reach one and the same landing simultaneously to actuate their floor stopping switches, in which case the car not under control to stop at such landing, would stop together with the car whose car button is set for stop at such point. Furthermore, by such independence, absolute control of stops for 55 each car by its buttons is retained and cannot be interfered with or canceled as, for example, by the automatic re-set operation of the hall buttons. It will be remembered that the first car intercepted at a floor will re-set the hall buttons, and hence, without this independence of circuits, such re-setting might 60

cancel the stop for the same floor, as registered by the car button of the second car coming along in the same direction, so the car would not stop to let off its passenger unless the car button was again pressed. 70

An operator may for certain contingencies desire to transfer the stopping effect of the parallel system of circuits and apparatus as rendered operable by the hall push-button system, and to accomplish such result, he actuates the switch 33 in the car to open both the "up" and "down" feed wire circuits 58 and 59. The "down" wire circuit is opened before it connects through switch 33 with the stop switches at all but the first floor, and the "up" wire circuit is opened before it connects through switch 33 with the stop switches at all but the upper floor. Since these feed wires 58 and 59 are subject to the control of the floor stopping switches and hall push-button system of circuits, such system by open circuiting said wires is thereby rendered ineffective even though the hall-buttons are pressed to effect a stop of any car of the bank whose transfer switch is held open and such car may thereafter continue its direction of travel as express to either end landing at which points the stopping effect of the stopping switches is effective. However, as will be noted, the system of circuits and apparatus as controlled by the car buttons is independent of said transfer switch and so remains effective to effect car stops to let car passengers off. Hence, by provision of such transfer switches an operator of any car can by actuating his switch at will at any intermediate point of car travel, render the intercepting control operative or inoperative with respect to his particular car system. 95

As will be noted, the operation of any one transfer switch effects the operation of its car system only, so that in effect, such actuation merely transfers the stopping effect of the intercepting system to the second car coming along in the same direction as the first and provided its transfer switch 33 is closed. 100

Coming now to the "up" and "down" direction relays 19 and 20 respectively, for establishing direction for car travel as effected by car switch operation, the "up" relay ordinarily remains in closed position during entire travel of the car in ascending, and the "down" relay functions likewise for descending direction of car travel. When the car reaches the top landing, the car cam 23 opens the switch 21 to de-energize winding 39 and thus open the "up" direction relay 19 whose back-contacts 74 will now close an energizing circuit for the "down" relay winding 37 and the "down" direction relay 20 will now close 115 to establish direction for "down" direction of car travel by car switch operation. In a like manner, when the car reaches the first floor landing, the car cam 23 opens the switch 22 to de-energize the "down" winding 37 of the 120 125 130

relay 20 which will open, and by closing its back contacts 38 close an energizing circuit for the "up" relay winding 39 which circuit may be traced as follows:—from the plus main 41, wire 75, contacts 38, wire 76, through "up" winding 39, wire 77, through back contacts 78 of the normally open auxiliary "up" relay switch 24, wire 80, thence through the switch 21 to the minus main by way of wire 81.

The automatic setting and re-setting of the direction relays by the car at the top and bottom landings having been pointed out, it will now be shown how the relays can be set by manual operation of the car switch to establish direction for reverse direction of car travel, such operation being effective at any intermediate point of car travel without actuation of the switches 21 and 22. To accomplish such result and assuming the "up" relay closed, the car switch segment 82 is actuated to engage contact 83, to close an energizing circuit for a winding 84 of the auxiliary "up" relay 24 whereby the latter will now operate to open its back contacts 78 thereby opening the energizing circuit for the "up" relay winding 39 and the "up" relay 19 will now close its back contacts 74 and by so doing, cause the "down" relay 20 to close in the manner before described so that at this time the car switch can be moved back to its neutral position and its movement continued so that the segment 34 engages the contacts 35 and the feed circuit 45 will now be directed by way of the "down" relay 20 to energize the down reversing switch winding 27. The "down" relay 20 will close now because of energization of its winding 37 by a circuit which may be traced as follows: from the plus wire, wire 75, back-contacts 74 of the "up" direction switch, through winding 37, and to the minus wire 21 by way of the switches 25 and 22.

An initial energizing circuit for the "down" reversing switch winding 27 may be traced by way of the plus wire 42, contacts 43 and 35 by way of the car switch segment 34, wire 44, winding 29, wire 45, contacts 32 of the stop switch S, wire 46, thence through the "down" reversing switch winding 27 by way of the "down" direction switch 20, to the minus main 49. The car switch need only momentarily be moved to on position and again centered and the reversing switch winding is maintained energized independently of the car switch by way of the circuit 51, and self-holding contacts 30 for the winding 29 of the relay 28.

The energizing circuit for the winding 84 may be traced as follows:—from the plus main 41, wires 75 and 85, through auxiliary contacts 86 on the up relay 19, wire 87, back contacts 88 on auxiliary "down" relay 25, wire 90, through winding 84, wire 91 and thence through the car switch contacts to the

minus main by way of wire 92. The back contacts 78 may be constructed in any well known manner so that when the relay 24 operates, its top contacts 93 will close before the bottom contacts 78 open which sequence is necessary since the circuit for the winding 84 is dependent on the closure of the contacts 86 of the "up" relay 19 dependent in turn on the closure of contacts 78. The top contacts 93 close a self-holding circuit for the winding 84 extending through the car switch contactors, so that by holding the car switch actuated for a short interval gives the "up" relay time to re-set itself and effect the setting of the "down" relay 25 before back contacts 95 of relay 24 are closed as effected by centering the car switch to open said self-holding circuit.

Thus it will be seen that for movement of the car in either direction, direction is established for reverse car travel by one way movement of the car switch segment 34 from its normal position, and as determined by whichever "up" or "down" direction relay is closed at the time the car switch is actuated, such closed relay being the factor which renders the actuation of the auxiliary relays 24 and 25 selectively operable by the one way movement of the car switch lever and said relays thereby operate to open or re-set whichever direction relay is closed, and to set or close the other one.

Referring to the car and hall push-buttons, since they are of the self re-setting type and their contactors and operating windings are included in the energizing circuit of the winding 31 of the stopping switch S, it is desirable in order to insure energization of the winding 31 to somewhat prolong the duration of contact between such contactors at the time of re-setting and such result may be effected in any well known manner as for example by provision of a somewhat elongated contactor as illustrated.

Circuits for the system of car B are shown complete as are also circuits for the bank of cars such as are interconnected. However, circuits for certain elements of the other two car systems, such as are individual to their particular systems, are not shown since to show same would be mere duplication of the car B system and tend toward complication of the drawing.

Reference will now be made to Fig. 2, which illustrates the intercepting push-button control system for a bank of three cars, the hoisting motor M and control for each being arranged for two speed operation. Selective speed change devices for the three car systems are designated G, H and K. The stop operation for the three car systems is controlled by the three sets of floor stopping switches L, M and N positioned in the elevator hatchways and actuated by their retractive car cams O. Each of these is in effect a

double cam held in an inoperative position by a spring 96, and actuated to operative position by an electro-magnet 97 controlled automatically to assume said operative position only

5 as the cars approach landings at which stops are to be made as controlled by the car and hall push-buttons.

In connection with Fig. 2, it will be mentioned that while the fast and slow speed controlling devices together with their interconnected controlling circuits for all three cars are shown complete, it is thought necessary for a clear understanding of the invention, to illustrate for only one of the car systems such other elements as go to complete one car system.

Such additional elements comprise "up" and "down" reversing switches R, R' and an accelerating magnet 196 which operates in a well known manner to control a sectional starting resistance 197 and series field winding 98 for the hoisting motor whose shunt field winding is designated 99. Fast speed operation of the motor is obtained in a well known manner by opening a short-circuit around a resistor 100 in the circuit of the slow field winding as effected by an electro-magnetically operated fast and slow speed switch 101, having a winding 125 whose energizing circuit in turn is controlled by a normally closed electro-magnetically operable auxiliary speed change switch P having a winding 102 whose energizing circuit is controlled by the selective speed change device G.

35 The selective speed change device comprises a worm 103 rotatable in accordance with the movement of the car through any well known type of connection as for example an endless chain, or cable, or a pair of tapes, connected to the car and engaging sprocket wheels, sheaves or reels at the ends of the car run, and operatively connected to the worm. Rotation of the worm is adapted to impart a reciprocating movement to "up" and "down" contactors 104 and 105 respectively to engage fixed contactors 106 and 107 corresponding to the floors, one set for "up" and one set for "down" directing of car travel. Contact strips 121 and 122 serve as feeders for said contactors 104 and 105. An additional contactor 108 fed from a contact strip 109, is given a reciprocating movement together with the contactors 104 and 105. This coacts with two sets of fixed contactors 146 to control an independent circuit subject to the control of the car buttons 13, 14 and 15 of the same type as in Fig. 1. "Up" and "down" hall push buttons designated 111 and 112 respectively in this instance control a mechanical interlocking arm 114, which normally locks an arm 115 in position shown to retain contactors 116 open-circuited, said contactors being closed by pressing a button to energize a winding 117 to unlock the arm 115. The hall push-button contactors are thus set to maintain circuits to ef-

fect operation of the auxiliary speed switch P as controlled through the agency of the selective speed change device G and in this manner automatic slow-down of the car is effected when a car is within a predetermined range (as determined by the selective speed change device) of any landing toward which the car is moving and at which stops are desired as selectively controlled by the car and hall push-buttons. Simultaneously with the slow down operation a winding 118 is energized to re-set or open-circuit the hall button contactors 116 corresponding to the stop made and the direction of car travel. Car stops are effected by operation of the stopping switch S to open its contactors 32, the energizing circuit for the winding of said switch being controlled in turn by normally open floor stopping switch contactors 119, the stopping switch arms having only a one-way movement from normal position as shown which movement is effected by the car cam O, whereby said contactors are closed momentarily, and subsequently the cam moves to retracted position and so releases the floor stopping switch to permit it to return to normal position to open-circuit its contactors through the action of a weight or spring 120.

The circuit for the winding 102 of the auxiliary speed change switch P divides at the car controlled "up" and "down" contactors 56 and 57 to provide "up" and "down" feed wires 123 and 124 connected to the "up" and "down" feeder strips 121 and 122 respectively, so that all "up" contactors of the speed controller for any one car system are in parallel and fed by way of the feeder 121 and contactor 104, and, likewise, the down contactors are in parallel and fed by way of the feeder 122 and contactor 105. However, the "up" contactors of all three selective speed change devices for any one floor, are connected in parallel by the wires 160, and the "down" contactors are similarly connected by wires 161, and since these circuits are subject to the control of the "up" and "down" hall push-button controlled contactors, means are provided whereby actuation of hall buttons at any landings, renders the speed change device G effective so that any car of the bank which is traveling toward a landing and in the direction corresponding to the button pressed, and is the first car to come along, will be automatically slowed down a predetermined distance from the landing as determined by the adjustment of its selective speed change device and will be subsequently stopped by the actuation of the floor stopping switch in the hatchway.

Closing of one or the other of the reversing switches R or R', to effect car starts is accomplished by momentary actuation of the car switch 18 and the relay 28 functions, the circuits being the same as in Fig. 1. I will assume now the car is started and ascending

from the first floor landing. The accelerating magnet will now function in a well-known manner to actuate its arms to short-circuit the starting resistance and series field

- 54 winding, and its last arm closes contactors 135 to close a circuit for the winding 125 of the fast speed switch 101, which switch will now open its contactors to introduce the resistance 100 in the circuit of the shunt field
- 55 winding of the hoisting motor and in this manner the motor will be caused to operate at its maximum speed or we will term it fast speed. The circuit for the winding 125 of the fast speed switch may be traced as follows:—from auxiliary contact 126 fed from the reversing switch disk 127, wire 128, through the winding 125, wire 129, contacts 135, wire 130, through contactors of the auxiliary speed switch P, and thence by wire 131 to the minus line. It will be noted that the circuit just traced included the normally closed contactors of the auxiliary speed switch P, hence when said switch P opens its contactors, the fast speed switch winding is thereby de-energized and the speed switch will again close its contactors 101 and thereby effect slow speed operation of the motor by short-circuiting the shunt field resistance.

- 56 Coming now to the control of the auxiliary fast speed switch P, assume the car is ascending to the third floor landing in which case the worm 103 actuates the contactors toward the left hand. When the car reaches a point a predetermined distance from the landing as determined by adjustment of the contactors of the selective speed change device G, the "up" contactor 104, will by momentary engagement with the third floor contactor on the speed controller close an energizing circuit for the auxiliary speed switch winding 102, which circuit may be traced as follows:—from a plus feed 136, through winding 102, wire 137, "up" direction relay contactors 56, thence to the third floor contactor on the selective device G by way of the feed wire 123, feeder strip 121, "up" contactor 104, to fixed third floor contactor 106, thence by the common "up" wire 160 to the third floor "up" push-button contactors 116, wire 138, thence through the reset winding 118 which will now function to open-circuit or re-set the contactors 116. The auxiliary speed switch P will now close its top contactors 139 to close at contacts 141 a self-holding circuit for its winding 102, said self-holding circuit including the auxiliary contactors 140 of whichever reversing switch is closed, so that in this manner the switch P is maintained closed with its normally closed contactors 101 open-circuited, after the speed controller G opens the initial energizing circuit just traced and until the reversing switch is open to effect a car stop.

57 The self-holding circuit for the winding 102 is the same as above traced to the wire

137 from which it branches and extends through contacts 139 of switch P and contacts 140 of whichever reversing switch is closed and thence to the minus wire.

58 The car cam O is held in its inoperative position by the spring 96, until the slow down operation is effected by operation of switch P, and the latter by operating, closes at contactors 141, an energizing circuit for the cam magnet 97 and the latter will now actuate the cam to an operative position so that its upper section or half will as the car approaches the third floor landing, actuate the floor stopping switch in the hatchway and thereby momentarily close said switch and when the car is substantially level with the landing, said cam will release the switch to permit it to return itself to normal or open position. Since this energizing circuit for the cam magnet is dependent on the closing operation of the switch P, and the latter is now controlled by the closed reversing switch, it will be seen then that the cam magnet will be de-energized by opening of the reversing switch and the cam will then be moved to its normal or inoperative position.

59 By momentary closure of the third floor stopping switch contactors 119, an energizing circuit is thereby closed for the winding 31 of the stopping switch S and the latter will now open its contactors 32 to open the self-holding circuit for the "up" reversing switch winding, and by so doing, effect opening of the reversing switch to cause the car to be brought to a stop.

60 The momentary energizing circuit for the winding 31 may be traced as follows:—from the plus wire 136, wire 142, through winding 31, wire 143, through floor stopping switch contactors 119, to wire 144 connecting all the floor stopping switches of any one floor in parallel, and thence by a common return wire 145 to the minus line.

61 In a like manner the car controlled buttons control the energizing circuit for the auxiliary speed switch winding 102 through the agency of the set of contactors 108, 109, and floor contactors 146, controlled by the selective speed change device G, and since these contactors and circuits are independent of the hall button controlled circuits, the absolute control of the car stops by the car buttons is retained in a manner and for the reasons stated in the description of Fig. 1.

62 Referring now to Fig. 3, the intercepting control system embodies apparatus and a system of circuits as constructed and arranged for multiple speed control, and to give an illustration of one well known type, each hoisting motor M is operated on a system identified in the elevator art as a "variable voltage control", which is essentially the well known Ward Leonard system. This system comprises more essentially a motor generator set T, the generator being electrically con-

5 nected by wires 147 to the armature brushes 148 of the hoisting motor M. Speed regulation of the hoisting motor is effected by varying the degree of strength of the generator field winding 149 through the agency of a set of graduated resistors 150, and reversal of the hoisting motor is effected by reversing the direction of current flow through said field winding of the generator, this being 10 controlled by any suitable type of reversing means which in the present instance are illustrated as electro-magnetically operated switches R, R'.

15 The reversing switch mechanism and speed regulating resistors are controlled by a modified form of switch mechanism somewhat like a car switch comprising a segment 153 to contact with two sets of contactors, one set for "up" and one for "down" designated 151 and 20 152 respectively, such elements and their functions being well known and needing no further description. However, the car switch segment according to the present invention is operated in reverse directions from 25 normal position by "up" and "down" actuating magnets 154 and 155 through a segmental gear and rack connection 156. These actuating magnets are energized one at a time by actuation of the car switch 18, in accordance 30 with whichever car controlled contactors 56 or 57 are closed, and the relay 28 controls a self-holding circuit for energized winding 154, I will say for example, so that the latter remains energized to permit the car switch 35 18 to be centered, and the magnet say 154, will maintain the segment 153 in full actuated position corresponding to maximum or fast speed operation of the hoisting motor. The self-holding circuit for the winding 154 may 40 be traced as follows:—from a plus wire 162, wire 163, relay contactors 30, wire 164, through relay winding 29, wire 165, contactors 166 of a slow-down initiating switch W, wire 167, "up" direction relay contactors 56, 45 wire 168, winding 154 and thence to the minus line by way of wire 169. The self-holding circuit just traced includes the normally closed contactors 166, so that by opening the circuit at this point the up winding 154 is 50 de-energized and the automatic slow-down operation of the hoisting motor is initiated.

55 The energizing circuit for the winding 170 is controlled by the selective speed change device G which functions in the same manner as in Fig. 2, subject to the control of the hall and car push-buttons, and in this case initiating the slow-down by effecting the de-energization of the actuating winding 154 to release the segment 153.

60 The worm 103 of the selective speed change device G in this instance is actuated by an endless chain 171 connected to the car at 172. This chain performs a double function; first, it actuates the device G, and, second, it causes 65 the segment 153 to return slowly to its cen-

ter position when the magnet 154 is de-energized. This is accomplished by rollers 173 on the chain which are arranged to engage "up" and "down" retroactive cams 174, 175 which are mechanically connected with the segment to cause the movement of the car to control the movement of the segment. One or the other of these cams, dependent on the direction of car travel, will coact with a roller as the car approaches a landing to prevent the quick return of the segment by its centering springs 177. As the car continues to move toward the landing, the roller permits the cam to swing on its pivot and permits the gradual automatic return of the segment. In this manner, the speed of the hoisting motor is gradually reduced and the car brought to a state of rest.

66 The connections between the cams and segment 153 comprise a pair of bell crank levers 178 and 179 connected by a pair of rods 180 fulcrumed at one end 181 to the segment and depending to form an angle and connecting at their other end to the bell crank levers. The "up" and "down" cams are connected to levers 182 and 183 respectively and pivotally supported at 176, each lever at its end being slotted and through pins 184 connects with its respective bell crank. By means of these connections, movement of the segment 153 in either direction from its neutral position as effected by magnets 154 and 155, effects only a one-way or unidirectional rocking movement of both cams to such positions as not to be engaged by such rollers on the chain as correspond to the landings which the car passes by. Furthermore, if a car either in ascending or descending overruns a landing at which it should stop, the roller will thereby engage a cam and through the connection just described, actuate the segment 153 in a reverse direction and in this manner effect a reverse movement of the car and return it to a level with the landing. Furthermore, if during loading or unloading of the car, it should move from a level with the landing, a roller will coact with the cams to effect a return movement of the car to a level with the landing.

67 In Fig. 3, only one car system of a bank of cars is shown complete in so far as is necessary for a clear understanding of the present invention, and in view of the detailed description already given for the selective speed change device G, together with the hall and car button controlled circuits as embodied in Fig. 2, it is not thought necessary to repeat in detail such description for said elements as embodied in Fig. 3, nor to go further with 120 illustration.

68 As an alternative type of mechanism to be substituted for and having the same function as the plurality of stopping switches L of the type positioned in the elevator hatchway as 130

illustrated in Fig. 2, an automatic selective stop controlling mechanism X of the unitary type as illustrated in Fig. 4, may be employed. This unitary stop mechanism comprises a series of pivotally supported floor control switches 200 adapted for rotation bodily by a member 201 to which the switches 200 are connected by brackets 202 for independent adjustment. The member 201 is adapted for rotation at a relatively slow rate and in proportion to the movement of the car. Such rotation may be effected by operatively connecting the speed change worm shaft 103 with the shaft 203 through the intermediary of a suitable type of gear reduction mechanism as, for example, a sprocket and chain connection 204.

Rotation of the floor controller switches by the member 201 brings the switches into position successively to coact with a retractive cam 205 normally held in retracted position by a spring 206 and actuated to an operative position to engage a switch roller 207, by means of an electro-magnet 210 which by rocking a lever 208 rotates a cam 209 into position to push in a guided rod 211 to which the cam 205 is attached.

When the unitary stop mechanism is substituted for the floor stopping switches of Fig. 2, the cams O and magnet 97 of Fig. 2 are not used and the magnet 210 of Fig. 4 replaces the magnet 97 in the circuit as shown for the latter. Thus the magnet 210 will be energized in proper order or sequence to move the cam 205 to operative position. With the car approaching the landing in descending, the roller of the stopping switch corresponding to the floor stop, will engage the cam face 212 to close the floor switch contactors momentarily and by so doing effect a car stop in the same manner as do the floor stopping switches of Fig. 2. With the car approaching a landing in an ascending direction, a floor switch is closed to effect a car stop through its roller engaging the cam face 213. The spring 206 retains the cam 205 in an inoperative or retracted position so as not to be engaged by rollers of the floor switches corresponding to the landings which the car passes by.

As illustrated in Fig. 5, an alternative arrangement may be employed for controlling car stops of the two speed system illustrated in Fig. 2. This consists of a single non-directional retractive switch 220 of a novel construction together with independently adjustable "up" and "down" cams 221 and 222 respectively at each landing and all in a common plane in the hatchway. The switch and coacting cams are controlled automatically and selectively to control car stops for all the landings.

The stop switch comprises a pair of pivoted switch arms 226, each carrying a contactor 223 held normally closed (or in cir-

cuit-closing position) by a relatively light spring 224. One of said arms carries a roller 225. The two switch arms are normally held with the contactors 223 closed in a retractive position with rollers 225 out of the plane of the cams by a relatively heavy spring 227 so that the switch will not be actuated at floors which the car passes by. An electro-magnet 228 actuates the two switch arms as a unit with the contactors 223 closed so that the roller will be in position to coact with a hatchway cam at the desired floor landing. By such coaction, one of the switch arms is actuated to open-circuit said contactors and break the self-holding circuit for an energized reversing switch winding and effect automatic car stop.

In embodying this Fig. 5 arrangement of car stop controlling mechanism in the Fig. 2 system of circuits, the single switch on the car replaces the stop switch of Fig. 2 in the self-holding circuit of the reversing switch windings and all the hatchway switches to control car stop. The car cams O are also eliminated. The electro-magnet 228 is substituted in the circuit shown for the cam actuating magnet 97 in Fig. 2 to be controlled selectively by the speed change mechanism. Thus the stop switch is controlled automatically to move to a non-retracted position and functions selectively to effect car stops at any point or points determined by actuation of the car and hall push-buttons.

Such elements of an elevator system as door contacts and door locking means, a cam magnet to control the same, automatic limit stops and so forth, together with their associated circuits have not been incorporated herein since those skilled in the art may readily make such embodiment without departing from the spirit or scope of the present invention. Various modifications in details and arrangement of the parts shown herein might readily suggest themselves to those skilled in the art. Hence, I do not wish to be limited to the precise details of construction and arrangement of parts as shown.

What I claim is:

1. In an intercepting control system, the combination with a bank of cars, a hoisting motor for each car, "up" and "down" reversing switches for each hoisting motor, each having a winding and a self-holding circuit therefor to effect floor to floor movement of the car automatically, subsequently to car start as effected manually, a stop switch in said self-holding circuit having an operating winding, car controlled "up and down" direction switches for each car actuated at the car's limits to establish direction for reverse car travel, an energizing circuit for said stop switch operating winding of each system divided at said direction switches to form "up" and "down" circuits, floor-control circuit-controllers for each car operable automatically

in accordance with the car's position to control said "up" and "down" energizing circuit, all of said circuit-controllers for any one landing which correspond as to direction being electrically interconnected, one "up" and one "down" push-button actuated contactors for each intermediate landing to control respectively said "up" and "down" energizing circuits to control stop of all the cars which form the bank, so that any car of the bank which is first to reach landings at which buttons are set and whose direction of travel corresponds to buttons set will be automatically 10 intercepted at such landings by actuation of said stop switch for such first car, by causing its associated self-holding circuit to open, said contactors remaining in actuated position when the buttons are released, a re-set winding for each hall push-button in said "up" and "down" circuits arranged to be energized by any such first car which is so stopped to re-set the button which effected the stop, a set of car button actuated contactors for each car to control an additional energizing circuit for said stop-switch operating winding to control the latter whereby each set of car buttons controls its own car exclusively to effect automatic stops thereof successively at all landings toward which car travel is directed, said car button contactors remaining in actuated position when pressed, and means controlled automatically by each car to re-set its own set of car buttons, and a transfer switch for each car operable manually at will to open said hall push-button controlled energizing circuit for said stop switch winding of its individual system only, whereby the stopping effect of said hall-buttons is rendered ineffective and the car will continue as express to any desired point and the stopping effect of the hall-buttons is thereby transferred to another car of the bank.

2. In an intercepting control system, the combination with the car, a hoisting motor therefor, selectively operable push-button controlled circuits and apparatus to control the hoisting motor, "up" and "down" directional switches each having an operating winding, means operable by the car at its limits to open an energizing circuit of one winding to open its switch and to close an energizing circuit for the other winding to close its switch to establish direction for car travel in a reverse direction, and a car switch operable in a one-way direction from center position to effect car starts for either direction of car travel as determined by the setting of said direction switches by the car, and means operable by movement of said car switch from its center position in a reverse direction to said above one-way movement to re-set said direction switches to establish direction for car travel in a reverse direction to that as effected by the car setting at its limits.

3. In an intercepting control system for an elevator motor having variable speed regulation, the combination with the car, a hoisting motor, a speed controlling switch controlled to effect floor movement of the car automatically and at its fast speed rate, electro-magnetic means to control said switch, means to control an energizing circuit for said electro-magnetic means to effect operation of said speed switch to effect automatic slow-downs 70 selectively and successively at predetermined points related to landings toward which the car is moving comprising car and hall push-button controlled contactors, all which correspond to landings toward which the car is moving and to its direction of travel remaining in actuated or set position when their buttons are released and being re-set individually, and circuit-controlling mechanism actuatable in accordance with the position of the car to control the energizing circuit for said electro-magnetic means as rendered operable by such car and push-buttons as are in actuated or set position.

4. In an intercepting control system for an elevator motor having variable speed regulation, the combination with the car, a hoisting motor, a speed controlling switch, a speed-change switch to control said speed controlling switch to effect floor to floor movement of the car automatically and at its fast speed rate, electro-magnetic means to actuate said speed-change switch, means to control an energizing circuit for said electro-magnetic means to actuate said speed-change switch to effect operation of said speed controlling switch to effect automatic slow-downs 100 selectively and successively at predetermined points related to landings toward which the car is moving comprising car and hall push-button contactors, all which correspond to landings toward which the car is moving and to its direction of travel remaining in actuated or set position when their buttons are released and being automatically 105 re-set by the car, car controlled circuit-controllers normally open-circuited and closing a circuit momentarily in accordance with the car's position to momentarily energize said electro-magnetic means, and means rendered 110 effective by said speed-change switch to effect car stops comprising cam actuated floor stop circuit-controllers controlled in accordance with the car's position.

5. In an intercepting control system for a bank of cars having multi-speed regulation, each car system comprising a single circuit-controller in the car to render effective fast speed operation which is maintained independently of said circuit-controller so that 120 travel of the car is continued automatically, means comprising a self-holding circuit to maintain said automatic car movement, an electro-magnetically operable switch in said 125 maintaining circuit, means to control an ener-

- gizing circuit for said switch to effect operation thereof to effect automatic slow-down, comprising car and hall push-button controlled circuits and apparatus, the hall push-
5 buttons being maintained in actuated position when manually released, said circuits for any one landing which correspond as to direction being interconnected so that any one button at any landing will effect automatic slow-down of the first car to reach a predetermined point related to the landing provided the direction of car movement corresponds to the button actuated, a re-set winding for each hall-button, and means whereby
10 15 any such first car of the bank to be slowed-down closes energizing circuits for said re-set windings whereby said buttons which effect slow-downs are automatically re-set.
6. In an intercepting control system, the combination with the car, a hoisting motor, a switch in the car to control its starts only, a single switch to control all car stops for both directions of car travel, car and hall push-buttons, and normally open-circuited
20 25 floor-control circuit-controllers controlled in accordance with car position to control said stop switch to effect car stops successively and selectively at landings toward which the car is moving.
- 30 7. In an intercepting control system, the combination with the car, a hoisting motor, a motor closing switch mechanism therefor having an operating winding, a self-holding circuit for said winding, and a single normally closed circuit-controller in said circuit, controlled automatically in either direction of car movement and in accordance with car position to open said circuit to effect car stops selectively at predetermined points.
- 35 40 8. In an intercepting control system, the combination with the car, a hoisting motor, a single switch in the car to control car starts only, a single circuit-controller to control car stops only for both directions of car movement and for all landings, and car actuated circuit-controllers to control said single circuit-controller to effect stops successively and selectively at any landings toward which the car is moving.
- 45 50 50 In witness whereof, I have hereunto set my hand this 28th day of October, 1926.

ERNEST L. GALE.
